United States Patent Office

Des. 221,169
Patented July 13, 1971

221,169

BOWL OR SIMILAR ARTICLE

Frank J. Benes, Lancaster, Ohio, assignor to Ravenscroft Ltd., Lancaster, Ohio

Filed May 6, 1970, Ser. No. 22,836

Term of patent 14 years

Int. Cl. D7—01

U.S. Cl. D36—2

FIG. 1 is an elevational view of a bowl or similar article showing my new design in the size and proportions of a sauce bowl;

FIG. 2 is a top plan view thereof;

FIG. 3 is an elevational view of a bowl or similar article showing my new design in the size and proportions of a salad bowl; and

FIG. 4 is an elevational view of a bowl or similar article showing my new design in the size and proportions of a tureen.

I claim:

The ornamental design for a bowl or similar article, substantially as shown and described.
